UNITED STATES PATENT OFFICE.

THOMAS H. PERFIELD, OF OMAHA, NEBRASKA.

FILING-CASE FOR DISK RECORDS.

1,130,016.

Specification of Letters Patent.

Patented Mar. 2, 1915.

Application filed July 9, 1914. Serial No. 849,931.

To all whom it may concern:

Be it known that I, THOMAS H. PERFIELD, a citizen of the United States, residing at Omaha, in the county of Douglas and State 5 of Nebraska, have invented certain new and useful Improvements in Filing-Cases for Disk Records, of which the following is a specification.

This invention relates to an improvement 10 in filing cases useful in connection with the storage of phonographic disk records, and has for its principal object to provide such a construction and arrangement of parts that the device will be convenient in use and 15 may be economically manufactured.

Another object is to provide such a support for the disks that, when placed in the case, they will not become bent or buckled.

The invention includes a convenient in- 20 dex for assisting in finding any particular disk, and a plurality of brushes or sweeper members so arranged that dust will be automatically removed from the disks.

With the foregoing objects in view and 25 others to be mentioned hereinafter, the invention presents a novel construction, combination and arrangement of parts as described and claimed, and as illustrated in the drawing, wherein—

30 Figure 1 is a plan view of the device, the case being in section near its top, as on line 1 1 of Fig. 2. Fig. 2 is a section through the middle of the case, as on line 2 2 of Fig. 1. Fig. 3 is a vertical, front view of 35 the device, the doors being removed. Fig. 4 is a plan view of a series of connected housing sheets. Fig. 5 is a plan view of a movable spacing plate. Fig. 6 is a detail relating to Fig. 1, showing the index on the inner 40 side of a door. Fig. 7 is a plan view of a stationary spacing plate. Fig. 8 is a plan view of the bottom of one of the housing sheets.

Referring now to the drawing for a more 45 particular description, numerals 9, 10, 11, 12 and 13 respectively indicate the top, bottom, the two sides and back of a substantially rectangular case for containing phonographic disk records, the front of the case 50 being provided with doors 14 and 15. The use of the doors, however, is not important and in some instances may be dispensed with. The disk records are indicated at 16,

and in order that they will not become bent or buckled when stored, they are disposed 55 horizontally, one above another, in the case, and while supported in this position they will be relieved from stresses which otherwise, on account of their weight, would be directed edgewise, and bending is therefore 60 prevented.

Numerals 17 and 18 respectively indicate movable and stationary spacing plates, each having a thickness substantially equal to that of the disks and provided on its inner 65 edge with a concaved recess *a* conforming to the curvature of the disks. A plurality of housing sheets 19 are employed, each being disposed on the top of a disk and a plate 17 and 18. Since the outer edges *b* 70 of the spacing plates may engage the upright walls of the case while the walls of their recesses *a* engage the edges of the disks, said spacing plates may operate to prevent any edgewise sliding movement of 75 the disks and maintain them at the middle of the casing. Sheets 19 are preferably provided at their middle with apertures *d*, and by use of the spacing plates the disks are maintained normally with their central apertures *c* in line with said apertures *d* so that 80 any dust or similar accumulations falling through apertures *c* will not be deposited on said sheets.

The case may have any suitable size or 85 proportion, sheets 19 having an area substantially equal to the interior of said case. Sheets 19 are preferably connected at their rear ends by pins or other suitable keepers 90 20, their under sides being provided with brush-members 21 best shown in Fig. 8, and they are incised as indicated at *e* to provide tapered front ends of different widths to visibly bear the numerals *f* shown in Figs. 1 and 4, the upper sheets having lesser 95 widths than the lower, so that the numerals on all of the sheets may be visible.

To assemble the parts, the series of housing sheets shown in Fig. 4 is inserted in the case, the spacing plate 17 and 18 being employed in pairs and disposed between two adjacent sheets, a disk being disposed between each pair of adjacent spacing plates in recesses *a*. Each plate 17 has a part *h* which extends forwardly of its recess *a* and, 100 normally, extends forwardly of the disk, 105

and this extension *h* is provided with a projection or finger 22 having a head piece *k* adapted to bear a numeral for identifying it, and by reference to Fig. 1 it will be seen 5 that if a plate 17 is manually moved forwardly, subject to the resistance of a spring 23, the disk engaged thereby will also be moved forwardly, and may be removed from the case. After a disk has been moved forwardly a limited distance by use of a plate 17, it may move laterally into a recess 24 at the front of a plate 18, and therefore the removal of a disk may be effected by a limited forward movement of a plate 17. 10 15 By reference to Figs. 1, 2 and 3 it will be seen that, while plates 17 and 18 are employed in pairs, each plate 17 of one pair is disposed above a plate 18 of an adjacent pair, this being a convenient arrangement so 20 that the fingers 22 will be spaced such a distance apart that they may be conveniently grasped when it is desired to remove any particular disk 16. 25 For convenience, the door 14 is provided with numerals, indicated at *m* in Fig. 6, and on the lines *n* may be entered titles for the several disk records, said numerals corresponding to the numerals on the heads of fingers 22 and also corresponding to the 30 numerals on the housing sheets.

For brush members 21, velvet or other similar material may be employed to advantage, and mounted on the housing sheets. When the disks are inserted between or 35 withdrawn from the housing sheets they will make contact with these brush members, with the result that any dust which may have been deposited on the disks will be removed. It will be understood that the series of 40 housing sheets together with the spacing plates and disks may be readily removed from the case or may be placed therein, whenever desired, springs 23 being pressed outwardly for this purpose. The use of the 45 springs is not important, however, and they may be dispensed with, if desired, since operation would be substantially the same if omitted, the movement of each disk being independent of the other disks and under control, for its movements, of the particular spacing plate 17 which it engages.

While the use of housing sheets 19 is preferred, since they prevent a contact of the disks with each other, said housing sheets 50 may, in some instances, be dispensed with, and therefore I do not wish to limit myself to their use.

I claim:

1. In a filing case for disk records, the 55 combination of a receptacle, a plurality of spacing plates arranged in pairs and adapted to have their outer edges in engagement with the walls of the receptacle while disposed therein, the spacing plates of a pair 60 being disposed in horizontal alinement and

having concaved edges for engagement with opposed edges of a disk, one of said plates of a pair being movable forwardly of the receptacle for moving the disk which it engages. 70

2. In a filing case for disk records, the combination of a receptacle, a plurality of spacing plates arranged in pairs, the plates of each pair being provided with recesses opening on their inner edges and disposed 75 in horizontal alinement adjacent to each other to normally engage opposed edges of the disk, one of said plates having a forwardly projecting part and being movable for moving the disk which it engages. 80

3. In a filing case for disk records, the combination of a receptacle, a series of housing sheets disposed one above another in the receptacle, a plurality of spacing plates each having a thickness substantially equal to the 85 thickness of a disk, said plates being arranged in pairs between the housing sheets for engagement of their outer edges with the walls of the receptacle, their inner edges being provided with recesses for normal engagement 90 with the opposed edges of a disk, one of said plates being movable for moving the disk in engagement therewith. 95

4. In a filing case for disk records, the combination of a receptacle, a series of connected substantially parallel housing sheets disposed therein, a plurality of spacing plates each having a thickness substantially equal to the thickness of a disk, said plates being arranged in pairs between the housing sheets for engagement with the walls of the receptacle, their inner edges being formed with recesses for normal engagement 100 with the opposed edges of a disk, one of said plates being movable for disengaging the disk from the recess of the other plate and for moving said disk outwardly of said case. 105

5. In a filing case for disk records, the combination of a receptacle, a series of connected housing sheets disposed one above another in the receptacle, each having a convergent terminal bearing a designating character, a plurality of spacing plates each having a thickness corresponding approximately to the thickness of a disk, said plates being arranged in pairs between the housing sheets for engagement with the walls of the receptacle, their inner edges being provided with recesses for normal engagement 110 with the opposed edges of a disk, one of the spacing plates of each pair being provided with a finger bearing a designating character and being movable for disengaging the disk from the recess of the other plate of 115 said pair and for moving said disk outwardly of said case. 120

6. In a filing case for disk records, the combination of a receptacle, a plurality of horizontal housing sheets disposed therein 125

and provided on their sides with brush members, a plurality of spacing plates arranged in pairs between the housing sheets, the plates of each pair having concaved recesses formed in their inner edges for normally engaging the opposed edges of a disk, one of said plates of each pair being movable for moving the disk from the recess of

the other plate of said pair and for moving the disk across a brush member. ¹⁰

In testimony whereof, I have affixed my signature in presence of two witnesses.

THOMAS H. PERFIELD.
